(57) CLAIM

The ornamental design for a condiment dispenser, as shown and described.

DESCRIPTION

FIG. 1 is a perspective view of a condiment dispenser showing my new design.

FIG. 2 is a second perspective view taken from a position opposite to that of FIG. 1.

FIG. 3 is a top plan view thereof.

FIG. 4 is a side elevation view thereof.

FIG. 5 is a side elevation view thereof taken from a position opposite to that seen in FIG. 4; and,

FIG. 6 is a bottom plan view thereof.
